UNITED STATES PATENT OFFICE

RUFUS CHOATE, OF WASHINGTON, DISTRICT OF COLUMBIA

FOOD CARTON

Application filed January 6, 1930. Serial No. 418,857.

This invention relates to containers and aims to provide an improved or special container for food-stuffs to be carried away from the place of purchase.

5 It will be best understood by description with reference to the attached drawings illustrating one practical embodiment thereof in a familiar type of paper carton.

In said drawings:

10 Fig. 1 is a perspective view of the container with top applied and a novel funnel therein open;

Fig. 2 is a vertical section of the container with the funnel in its top closed; and

15 Fig. 3 is a plan view of sheet-material pieces from which the funnel is formed.

The illustrative container embodies a paraffin-treated paper carton 4 of the cylindrical form commonly used in delicatessen 20 or other stores for dispensing ice cream and other food-stuffs to be carried away by purchasers. Apart from its utility as a container for solid foods, it is specifically adapted to use with liquid preparations such 25 as soups and beverages for which the ordinary paper carton is not suited, so that purchasers thereof are obliged to bring pails or have the same placed in bottles, unless he wishes to incur the inconvenience of carrying 30 a package liable to spill its contents upon his hands or clothing.

According to this special design and construction, the top 5 of the carton is formed with a telescoping flange having angular 35 slots 5^a engaging with pins 6 at diametrically opposite points on the carton body in the manner of a so-called "bayonet joint". These pins may comprise ordinary rivet studs applied through or to the wall of the carton.

40 To the inside of the top's flange, separate pieces 7 and 8 of flexible tape are secured at diametrically opposed points, in this instance by rivets 9. These pieces of tape are attached together by a snap-fastening 10 so as to 45 provide a light handle for portage purposes. In such arrangement, the pieces loop or engage under the edge of said flange to relieve lifting strain on the points of securing and providing leverage thereon greatly aidful 50 in removing the top when turned to disen-

gage the locking pins. Moreover, a tighter bind to the carton body thus results.

In said top, a funnel opening 11 is formed to permit emptying (in the case of liquid content) without need for removing the top from 55 the carton. Into this opening is fitted a novel and special funnel member formed of sheet-material such as light paraffin-treated paper or thin cardboard. The component pieces or parts cut to pattern are represented 60 in Fig. 3. The principal part 12 is folded angularly on the dotted lines to form a sluice-like member having a bottom portion 12^a, sides 12^b, side flanges 12^c and a lift flap 12^d. To the bottom portion 12^a of this part the 65 over-extending part 13, which is bendable along its dotted line is secured by adhesive or otherwise, and to the side flanges 12^c thereof the part 14 is similarly secured as a brace.

The funnel member thus formed is fitted 70 into the aforesaid opening with the part 13 resting on the outer surface of the top over said opening and with the side flanges 12^b of the part 12 as braced by the part 14 adapted to engage under the inside surface of the top 75 along the opening's edges. The flap-like portion 13^a of the part 13 is then secured to the top by adhesive or otherwise, while the lift-flap 12^d is bent to project upwardly for easy 80 grasp by the fingers. The funnel member is accordingly adapted to outward and inward swing with bending of the part 13 along its dotted line as the axis and enables the carton to be emptied of liquid contents without sloshing over the edge and down its sides as 85 with the ordinary carton. When closed, it of course seals the opening.

It may be desirable in some cases to provide an air hole 15 in the top, in which event a segmental piece 16 of the same material as 90 the funnel may be secured to swing on pivotal fastening over and clear of such hole.

The container or carton may be made in various forms and with various modifications of the funnel member without departing 95 from the spirit and scope of the invention so that it will be understood the appended claims are not intended to limit the same to the specific construction shown.

Having thus described my invention, what 100

I claim as new and desire to secure by Letters Patent of the United States is:

1. A food and liquid container comprising an open-ended carton or box having an over-engaging top lockably fitted thereto and a strap handle having opposite ends extending under and secured to the inner side of the top's edges so as to exert an outward springing and removing leverage thereon with upward pull when said top is unlocked or released.
2. A food and liquid container comprising an open-ended carton or box having a marginally flanged top lockably fitted thereover and a tape handle having its opposite ends extending under and secured to the inner side of the top's flange at opposed points so as to exert a lifting and removing leverage thereon with upward pull when said top is unlocked or released.
3. A food and liquid container comprising an open-ended carton or box having pins extended from its sides; a flanged top fitting over the open end of the carton having slots engaging the pins thereof in a locking connection and a hinged spout forming a closure for a drainage opening therein and a flexible handle of tape having its opposite ends secured to the inner side of the top so as to extend under the edges thereof and exert an outward-spreading and removing leverage thereon with upward pull when said top is unlocked or released from its connection with the carton.
4. A container comprising an open-ended cylindrical carton having a flanged top engaging thereover and fastened thereto by a locking connection; and a strap handle with opposite ends secured on the inner side of the top's flange at opposed points so as to extend under the edge thereof and exert an outward-spreading and removing leverage thereon with upward pull when said top is unlocked or released from its connection with the carton.

In testimony whereof I affix my signature.

RUFUS CHOATE.
